Primary Examiner—Raphael Barkai

(57) **CLAIM**

The ornamental design for television cover with slits, as shown and described.

DESCRIPTION

FIG. 1 is a front perspective view of a television cover with slits showing my new design, the broken lines are for illustrative purposes only and form no part of the claimed design; and,

FIG. 2 is a front elevational view thereof.

1 Claim, 2 Drawing Sheets

FIG. 1

FIG. 2
